ADAPTER FOR UNIVERSAL LEVER SWITCHES

Filed March 22, 1948

FIG. 2

FIG. 4

INVENTOR.

RUDOLF POPP
BY *Norman L. Mueller*

UNITED STATES PATENT OFFICE

2,608,105

ADAPTER FOR UNIVERSAL LEVER SWITCHES

Rudolf Popp, Valparaiso, Ind., assignor to McGill Manufacturing Company, Inc., Valparaiso, Ind., a corporation of Indiana

Application March 22, 1948, Serial No. 16,253

5 Claims. (Cl. 74—501)

1

This invention relates to universal lever switches, and it is particularly concerned with adapters for increasing the utility of such switches.

In a switch of this type, the universal lever which is employed to actuate the switch contacts normally is positioned so that it can conveniently be rocked on its fulcrum by a force applied directly to the lever. For instance, the lever may extend laterally while the actuating force is applied downwardly to it. Sometimes, however, the switch is positioned so that the operating force must be applied in the same direction as that in which the universal lever extends. For example, the switch may be mounted on a ceiling fixture with the universal lever extending downwardly, and with a pull chain or the like depending from the lever. When the universal lever is subjected to a direct pull in this manner, it does not function as a lever but merely as a link, and under these circumstances the switch requires a rather hard pull for its operation. The fixture is also subjected to greater stress when the lever is directly pulled than when it is rocked on its fulcrum.

An object of the present invention is to provide an improved adapter which enables a universal lever switch to be readily operated as a lever even though the pull is in a direction parallel to that in which the universal lever extends.

A further object is to provide an improved adapter for a universal lever switch mounted in a ceiling fixture or the like which enables the switch to be operated as easily when the universal lever is extending downwardly from the fixture as would normally be the case when the lever extends laterally.

A still further object is to provide a novel adapter of simple and economical construction having the aforesaid advantages and which can readily be attached to existing makes of universal lever switches.

In accordance with a feature of the invention, an operating arm is attached to the universal lever of a fixture switch or the like to extend substantially at right angles from the lever, and a pull chain or cord for operating the switch is connected to the outer end of this arm. When the operating arm is pulled, it causes the universal lever to be rocked on its fulcrum, and in this way

the switch is operated with its customary ease instead of requiring an unduly hard pull.

The invention also provides a guide member for the arm of the adapter, this member being conveniently mounted on the fixture by the fastening means for the switch and serving to prevent the arm from turning about the longitudinal axis of the lever, as well as limiting the extent of its swing.

10 The foregoing and other objects, features and advantages of this invention will be better understood by reference to the following detailed description taken in connection with the accompanying drawing, in which:

15 Fig. 1 is a side elevational view of a universal lever switch equipped with an adapter embodying the principles of the invention;

Fig. 2 is a detailed elevational view showing the arm of the adapter;

20 Fig. 3 is a plan view of the arm;

Fig. 4 is a perspective view of the guide for the adapter arm;

Fig. 5 is a view similar to Fig. 1 but showing a modified form of the invention;

25 Fig. 6 is a perspective view of a modified guide; and

Fig. 7 is a perspective view of the operating arm of the modified adapter.

In practicing the invention, an operating arm,

30 which may be formed out of a sheet metal stamping or a length of hard wire, is attached at one end thereof to the universal lever of the switch. Preferably the arm is so constructed that it can be snapped on to the lever. A forked guide mem-

35 ber adapted for slide on attachment to the switch is secured at its upper end to the wall of the fixture by a mounting nut for the switch. This guide member has a vertical slot or guide opening through which the arm of the adapter extends.

40 The lower end of the slot is closed to limit downward swing of the arm. A chain or cord is attached to the outer end of the arm for actuating the switch.

45 Referring now to the drawing, Fig. 1 shows the manner in which a typical universal lever switch 10 of well known construction may be mounted on the wall 12 of a fixture, with the universal lever 14 of the switch 10 extending downwardly from the wall 12. As is usual in such structures, the lever 14 is seated at its upper

end on a threaded mounting stem (not visible) of the switch. A mounting nut 16 on this mounting stem secures the switch 10 to the fixture wall 12. The universal lever 14 normally is adapted to be rocked from a position such as indicated by full lines in Fig. 1 to the position represented by broken lines for operating the switch 10. However, when the switch 10 is so disposed that the lever 14 extends downwardly from a high point such as a ceiling fixture, as in the present instance, it has not been convenient or possible to rock the lever 14 on its fulcrum. This has been due to the fact that the pulling element, such as the bead chain 18, customarily has been directly connected to the lever 14. In such instances a relatively hard pull on the chain 18 was required to actuate the switch contacts.

In accordance with the present invention, an adapter arm 20 is attached at one end thereof to the shank of the universal lever 14 and extends laterally therefrom. The pull chain 18 or like member, instead of depending from the lever 14, is connected to the outer end of the arm 20 by a suitable coupler 22. When the chain 18 is pulled downwardly, the arm 20 moves from its full-line position into its broken-line position, Fig. 1, and causes the lever 14 to be rocked as indicated.

Referring now to Figs. 2 and 3, the arm 20 in this embodiment of the invention is formed from a flat blank. The inner end of the arm 20 is curved into a hook, as indicated at 24, so that the arm 20 can be snapped onto the shank of the lever 14. The conventional annular beads 26 and 28 on the lever 14 assist in retaining the hooked end 24 engaged with lever 14.

In order to prevent the arm 20 from turning about the longitudinal axis of the lever 14, a guide member 30 is provided. This guide member is forked at its upper end 32, as shown in Fig. 4, and the forked end 32 is inserted between the mounting nut 16 and the fixture wall 12, being held firmly in position by the nut 16 when it is tightened. The guide member 32 curves inwardly to a slight extent at its lower end 34, and is provided with a vertically extending slot 36 to receive the arm 20. The slot 36 guides the arm 20 as the latter is swung and confines the movement of the arm 20 to a vertical plane. The lower end of the slot 36 is closed so as to limit the downward swing of the arm 20, thus preventing damage to the switch.

Considering now the modification illustrated in Figs. 5, 6 and 7, the arm 40 of the adapter is formed of hard wire which is coiled at its inner end, as indicated at 42, to grip the shank of the universal lever 14. The coils 42 are sufficiently yielding so that they may be slipped over the bead 28 on the lever 14, but the wire itself is sufficiently rigid so that it does not bend appreciably when subjected to a downward pull. The outer end of the arm 40 is formed into a loop 44 to receive a pull cord 46 or the like.

A guide member 47 for the arm 40 may likewise be made of hard wire bent into a U-shape and having lateral extensions 48 at its upper end adapted to be slipped between the mounting nut 16 and the fixture wall 12. The bight at the lower end of the guide 46 limits the downward swing of the arm 40.

From the foregoing description it can be seen that I have provided a universal lever switch adapter of simple and cheap construction which is capable of being attached to the universal lever switches which are presently on the market

to increase their utility. This adapter enables universal lever switches to be employed in situations where formerly they were regarded as not feasible or disadvantageous. Additional features of this adapter not specifically mentioned herein above may be apparent to those skilled in the art.

While I have illustrated and described a preferred embodiment of my invention, such embodiment obviously is capable of being modified without departing from the principles set forth hereinabove, and it is intended to cover all such modifications by the appended claims.

I claim:

- 15 1. In a universal lever switch mechanism arranged for mounting in an elevated position with the universal lever thereof extending downwardly, an adapter for enabling the universal lever to be rocked by a downward pull, comprising a laterally extending arm respectively adapted at opposite ends thereof for attachment to the universal lever and for connection to a pull member for actuating the switch, and a guide adapted for slide-on attachment to the switch and cooperating with said arm to prevent said arm from turning on the lever axis.
- 20 2. In a switch having a universal lever for actuating the switch, the combination of an arm on the universal lever extending transversely therefrom and adapted to transmit to the universal lever an actuating force applied parallel to the lever, said arm comprising a sheet metal stamping having a hook portion at one end thereof to embrace the shank of the universal lever and a guide mounted on the switch to prevent turning of said arm about the longitudinal axis of the universal lever and also limiting the rocking movement of said arm when the same is actuated by a force applied thereto.
- 25 3. In a switch having a universal lever for actuating the switch, the combination of an arm on the universal lever extending transversely therefrom for enabling the lever to be rocked by a force applied parallel to the lever, said arm comprising a length of stiff wire coiled at one end thereof around the shank of the universal lever and a guide mounted on the switch to prevent turning of said arm about the longitudinal axis of the universal lever and also limiting the rocking movement of said arm when the same is actuated by a force applied thereto.
- 30 4. An adapter for enabling a universal lever switch to be operated by a force substantially parallel with and transversely spaced from the longitudinal axis of the universal lever, such adapter comprising a substantially rigid arm having a portion for gripping the universal lever and another portion extending transversely from said gripping portion to afford a leverage for the switch-operating force, and a guide member adapted to be mounted on the switch in a slide on operation and cooperating with said arm to prevent said arm from turning on said lever axis.
- 35 5. An adapter for enabling a universal lever switch to be operated by a force acting substantially parallel to the longitudinal axis of said lever, said adapter including a guide member comprising a supporting portion designed to fit the housing of said switch, said supporting portion having an arm integral therewith and extending therefrom, said arm having an elongated slot therein, and a lever arm movably disposed within said slot, said lever arm being secured on one of its ends to said universal lever, and secured on the other of its ends to an actuating

- 40 6. An adapter for enabling a universal lever switch to be operated by a force acting substantially parallel to the longitudinal axis of said lever, said adapter including a guide member comprising a supporting portion designed to fit the housing of said switch, said supporting portion having an arm integral therewith and extending therefrom, said arm having an elongated slot therein, and a lever arm movably disposed within said slot, said lever arm being secured on one of its ends to said universal lever, and secured on the other of its ends to an actuating
- 45 7. An adapter for enabling a universal lever switch to be operated by a force acting substantially parallel to the longitudinal axis of said lever, said adapter including a guide member comprising a supporting portion designed to fit the housing of said switch, said supporting portion having an arm integral therewith and extending therefrom, said arm having an elongated slot therein, and a lever arm movably disposed within said slot, said lever arm being secured on one of its ends to said universal lever, and secured on the other of its ends to an actuating
- 50 8. An adapter for enabling a universal lever switch to be operated by a force acting substantially parallel to the longitudinal axis of said lever, said adapter including a guide member comprising a supporting portion designed to fit the housing of said switch, said supporting portion having an arm integral therewith and extending therefrom, said arm having an elongated slot therein, and a lever arm movably disposed within said slot, said lever arm being secured on one of its ends to said universal lever, and secured on the other of its ends to an actuating
- 55 9. An adapter for enabling a universal lever switch to be operated by a force acting substantially parallel to the longitudinal axis of said lever, said adapter including a guide member comprising a supporting portion designed to fit the housing of said switch, said supporting portion having an arm integral therewith and extending therefrom, said arm having an elongated slot therein, and a lever arm movably disposed within said slot, said lever arm being secured on one of its ends to said universal lever, and secured on the other of its ends to an actuating
- 60 10. An adapter for enabling a universal lever switch to be operated by a force acting substantially parallel to the longitudinal axis of said lever, said adapter including a guide member comprising a supporting portion designed to fit the housing of said switch, said supporting portion having an arm integral therewith and extending therefrom, said arm having an elongated slot therein, and a lever arm movably disposed within said slot, said lever arm being secured on one of its ends to said universal lever, and secured on the other of its ends to an actuating
- 65 11. An adapter for enabling a universal lever switch to be operated by a force acting substantially parallel to the longitudinal axis of said lever, said adapter including a guide member comprising a supporting portion designed to fit the housing of said switch, said supporting portion having an arm integral therewith and extending therefrom, said arm having an elongated slot therein, and a lever arm movably disposed within said slot, said lever arm being secured on one of its ends to said universal lever, and secured on the other of its ends to an actuating
- 70 12. An adapter for enabling a universal lever switch to be operated by a force acting substantially parallel to the longitudinal axis of said lever, said adapter including a guide member comprising a supporting portion designed to fit the housing of said switch, said supporting portion having an arm integral therewith and extending therefrom, said arm having an elongated slot therein, and a lever arm movably disposed within said slot, said lever arm being secured on one of its ends to said universal lever, and secured on the other of its ends to an actuating
- 75 13. An adapter for enabling a universal lever switch to be operated by a force acting substantially parallel to the longitudinal axis of said lever, said adapter including a guide member comprising a supporting portion designed to fit the housing of said switch, said supporting portion having an arm integral therewith and extending therefrom, said arm having an elongated slot therein, and a lever arm movably disposed within said slot, said lever arm being secured on one of its ends to said universal lever, and secured on the other of its ends to an actuating

5

means movable along a line parallel to the longitudinal axis of said lever.
